Fig. 1 is a top plan view of a cable puller embodying my new design;

Fig. 2 is a side view thereof taken slightly in perspective;

Fig. 3 is a view thereof taken slightly in perspective, showing the side opposite that shown in Fig. 2;

Fig. 4 is a right end view thereof taken slightly in perspective, portions of the left end being omitted for convenience of illustration;

Fig. 5 is a left end view thereof taken slightly in perspective;

Fig. 6 is a top plan view of a modified form thereof;

Fig. 7 is a side view of the modified form, taken slightly in perspective, the opposite side being substantially the same; and

Fig. 8 is an end view of the modified form, taken slightly in perspective, the opposite end being substantially the same.

Figs. 2, 3, 4 and 8 are on a slightly reduced scale.
I claim:

The ornamental design for a cable puller, substantially as shown and described.
